UNITED STATES PATENT OFFICE

165,909

ELECTRIC IRON

Francesco Collura, New York, N. Y., assignor to
Steam Electric Products Limited, Toronto, On-
tario, Canada

Application December 12, 1950, Serial No. 13,397
In Canada June 17, 1950

Term of patent 14 years

(Cl. D49—6)

To all whom it may concern:

Be it known that I, Francesco Collura, a citizen of the United States of America, residing at New York, State of New York, have invented a new, original, and ornamental Design for Electric Irons, of which the following is a specification, reference being had to the accompanying drawing, forming a part hereof.

Fig. 1 is a top perspective view of an electric iron, viewed from the rear and from one side, showing my new design;

Fig. 2 is a top perspective view thereof, viewed from the front and from the other side;

Fig. 3 is a bottom plan view thereof.

I claim:

The ornamental design for an electric iron, as shown.

FRANCESCO COLLURA.
